UNITED STATES PATENT OFFICE

ARTHUR STOCKSTROM, OF ST. LOUIS, MISSOURI, ASSIGNOR TO AMERICAN STOVE COMPANY, OF ST. LOUIS, MISSOURI, A CORPORATION OF NEW JERSEY

SWINGING COVER FOR THE TOP BURNER PORTION OF STOVES

Application filed March 21, 1929. Serial No. 348,766.

This invention relates to improvements in swinging covers for the top burner portion of stoves and it pertains to a swinging cover that is adapted to swing over the top burner portion when it is not being used, and is adapted to be swung into an upright backward position when it is to be used.

Manufacturers have realized that the top burner portion of a range being constantly exposed collects dust and dirt and presents an unseemly appearance to the range when it is not in use.

The broad idea of the present improvement is to protect the exposed burners and the exposed open part from the collection of dirt and dust when not in use and to give the stove a finished appearance when it is not in use.

Manufacturers realizing these defects in ordinary gas ranges have been for some time engaged in overcoming the above faults in ordinary ranges. So far as I am aware however the means used for protecting the open part of the ranges have not accomplished the result in a manner which will produce the above advantages.

The primary object of the present improvement may be said to embody the idea of hinging a cover to the range whereby when the stove is in use the same is in vertical position at the rear of the top portion, and when it is not in use the cover is simply swung forward over the open portion and protects it and at the same time greatly improves the appearance of the range.

A further improvement is to make this swinging protecting cover so that when the open portion of the range is in use the cover acts as a splash back for the top burners and furthermore the improvement when lifted over the top burner portions acts as a high top shelf upon which articles can be placed.

A further improvement is in so constructing this protecting cover that it is hinged at points located inside of the rear edge of the open part whereby the cover when it is closed over the burners still further acts to improve the appearance of the range.

The ranges as ordinarily built have at one side of the burner top a roasting oven and a

broiler oven and the roasting oven extends considerably above the open burner portion of the range.

Another improvement is making this protecting swinging cover portion of a depth equal to the space between the open burner portion and the top of the roasting oven whereby when the cover is in its closed position then its top surface is in a line with the top surface of the roasting oven, the same presenting a stove which in appearance is quite attractive and at the same time when the cover is moved to its vertical position a shelf is provided that is as wide as the distance between the top burner part and the top of the roasting oven.

There are certain other features of the invention which will be described and shown hereinafter.

Figure 1 is a perspective view of a gas range with my improved cover applied thereto and the cover raised to expose the open burner portion.

Figure 2 is a perspective view of a range with my improved cover in its closed position.

Figure 3 is a cross sectional view taken on the line 3—3 of Figure 2.

Figure 4 is a perspective view of the rear end of the range with my improved swinging cover applied to it and shown in its closed position.

Figure 5 is a rear perspective view of the range with the protecting cover raised.

Figure 6 is a horizontal central section taken through the cover portion on the line 6—6 of Fig. 3.

Figure 7 is a sectional perspective view taken horizontally through one end of the swinging cover.

Referring to Figure 1 of the drawings which shows this improvement applied to a gas range and in which figure, 1 indicates the roasting oven and 2 the broiling oven. Located to one side of these ovens is the top burner portion 3. This top burner portion is located in a horizontal plane below the horizontal plane of the top 4 of the roasting oven. Thus far I have explained the usual construction of gas ranges of this type.

The range shown in Figure 1 has its gas manifold concealed, which however forms no part of the present invention, and passing through the front portion 5 below the open burner portion 3 are a plurality of handles 6 which are connected with the top burners (not shown) located in the housing of the top burner portion.

The present improvement comprises a hinged cover A which when in its horizontal position shown in Figures 2 and 3 covers the top burner portion 3 and therefore protects it from observation when the burners are not in operation and also protects the burners from accumulating dirt. This cover comprises in the construction herein shown a portion 11 which is the top thereof when in the horizontal closed position and B is the front of this cover A while its ends consist of the outer walls 13 and 14. The top portion 11 and its side portion 13 and 14 each are provided with an inner wall 15 and 16. These inner walls are spaced from the outer walls and are enameled. Also the top part 11 has an inner wall 18 in spaced relation thereto, the inner wall 18 being also enameled whereby when the cover A is turned up in the position shown in Figure 1 this wall 18 forms a splash plate located at the rear of the top burner portion 3. The front ends 19 of Figure 7 of the outer walls 13 and 14 are bent in opposite directions, and the front ends of the inner walls 15 and 16 are bent so that their ends are in telescopic relation as shown.

In the specific construction and arrangement of the ends 20 in the construction shown in Figure 7, the rear end *a* of the inner wall 16 is bent outwardly and the corresponding end *b* of the inner wall 18 passes outwardly between the inwardly bent end *a* and the inwardly bent end *c* of the wall 14, while the outer wall 11 has its end *d* bent around and inwardly and resting against the inwardly bent end *c* of the wall 14. All the ends of these walls are clamped together in any desired manner. The ends of the vertical walls 13 and 15 at the opposite side of the cover A and the opposite ends of the walls 29 and 29' are constructed and arranged in the same relation as that described above.

By reference to Figures 1 and 7 it will be noted that the lower ends of the cover A are pivotally connected with the edges of the top burner portion 3. The particular manner of hinging these parts is shown in Figure 7. From this figure it will be observed that one portion 21 of the hinge passes through the top burner part 3 and is suitably secured to it while the other member of the hinge 22 is located between the walls 16 and 21' and 14, the said members 26 being riveted to the bent end 20' of the inner wall 15. It will be understood from the foregoing that when the cover A is turned in its horizontal position over the top plate 3 for

the purpose of concealing it and its burners (not shown) that it is held in this position by gravity.

For the purpose of assisting in raising this cover to a vertical position a suitable spring and link connection 23 is attached to both sides of the cover. This construction involves the links 24 with their upper ends 25 pivoted to members 26 that pass through openings 26' made in the link end 22' while the opposite ends of the links 24 are attached by means of a spring 27 to the rear wall 28 of the range housing. This is a contracting spring so that it assists in the lifting of the cover and also prevents the cover from slamming when closed to a horizontal position.

By reference to Figures 3 and 6 the special construction of the front 11 is shown. It consists essentially of a central portion 29 having its inner ends 30 turned inward and a surrounding member 31 having its inner ends bent inwardly and telescoping said ends 30, the telescoping ends and the corresponding end 32 of the splash plate 18 are connected by suitable bolts 33 while the outer edge of the part 31 is connected by bolts 34 with an inwardly turned end of the top portion 11.

Attention is directed to the fact that the inner end of the cover is open so that when the cover is turned to vertical position there is nothing to interfere with the burner top 3. When the range is set up for operation the rear wall thereof is placed close to the wall of the room so that it is immaterial that the inner end of the swinging cover is not closed.

Attention is also called to the fact that the wall 18 stops at the top burner portion 3 so that there is nothing to interfere with the top burner portion 3 when it is being turned to vertical position. However the opposite or outer wall 13 does extend downward as at 35 and it is located outside of the range wall 36 so that it telescopes the said wall as clearly shown.

Furthermore the splash plate 18 does not extend beyond the member 22', which member when the cover is raised rests on the top of the open burner top portion. From Figure 3 it will also be seen that the top portion 11 is extended inward beyond the inner end of the splash plate 18 as shown at 11' so that when the cover is turned to horizontal position this part prevents any opening throughout the width of the range, thus leaving the top of the range as shown in Figures 1 and 2.

The location of the hinged members will be such as to prevent the extended portion 11' of the top 11 from swinging in the arc of a circle substantially beyond the rear wall 37 of the range.

This invention is also adapted to form a covered cooking compartment, that is to say this form of cover gives sufficient room when

it is closed between the top 11 and the top burner part 3 to receive a teapot or a frying pan or other cooking utensils. This cover or compartment as shown has its rear end 5 open so that smoke, steam etc. will pass out the open rear end and at the same time is also adapted to form a cover as herein previously described. For instance should occasion arise cooking can be done in the compartment when it is in its downward or closed position and thus hiding or concealing what is being cooked, and at the same time permit free access thereto by lifting the said cover. For instance anyone cooking with 10 the cover raised and anyone should call, can conceal what is cooking by simply lowering this cover and the cooking would proceed. At the same time the cover is adapted when lowered to conceal this top burner portion 20 and when the cover is raised to act as a splash back, as previously described.

While I have described and shown this improvement for use on a gas range, it can be used on ranges for covering and protecting 25 a top burner portion of ranges using other kinds of fuel or means for cooking purposes, therefore my improvement is not limited in its broadest sense to gas ranges.

Having thus described my invention what 30 I claim and desire to secure by Letters Patent is:

1. The combination with a gas range having a top burner portion, a protecting swinging cover provided with a flange extending 35 partly around the burner portion, the inner ends of the flange pivotally supported by the structure, an outer flange adapted to telescope the outer wall of the open burner structure when the parts are raised and the inner side flange cut away from a point below the 40 said burner portion whereby the parts operate as described.

2. The combination with a gas range having a top burner structure, an oven structure 45 at one side of the top burner structure and extending thereabove, of a swinging protecting cover for the top burner structure, the swinging cover having an inwardly extending flange of a depth substantially equal to 50 the height of the oven above the top burner structure, the inner edges of the flange pivotally connected with the top burner structure and the top of the cover when it is raised extending below the open burner structure 55 whereby when the cover is in its horizontal position it extends over the top burner structure.

3. The combination with a gas range having a top burner structure, an oven structure 60 at one side thereof and extending above the top burner structure, of a swinging cover for the top burner structure, the said cover having a flange of a depth substantially equal to the height of the oven above the top burner 65 structure, the inner edges of the flange piv-

otally connected with the top burner structure, the part of the cover extending below the top burner structure when the cover is raised, that part of the flange opposite the oven telescoping the outer vertical wall of 70 the top burner structure and the flange nearest the oven cut away, whereby when the cover is lifted a space is not required between the oven and the top burner structure and whereby the protecting cover can be 75 raised and lowered without interference.

4. A gas range comprising a top burner portion and a protecting cover therefor, said cover having a flange around its outer end and part way around one side, the inner end 80 of one side flange being pivotally connected with said top portion and the other side flange pivoted in a line with the said pivoted flange, part of the cover extending beyond the ends of the flange and adapted to extend outside of and parallel the rear wall of said top portion as described.

5. A gas range comprising a top burner portion, a protecting cover therefor, said cover having its front edge and its sides provided with an inwardly extending flange portion, said flange stopping at points inside of the rear edge of the cover, the forward ends of the side flanges pivotally connected with the said top burner portion, whereby when the cover is lowered the top burner portion is concealed and when the cover is elevated the rear part that extends back of the side flanges lies behind the rear wall of the top portion. 95

6. A gas range comprising a top burner 100 portion, a swinging protecting cover for the top portion adapted to conceal the top portion when the cover is lowered, said protecting cover having its outer end and side portions provided with an inwardly extending flange, the flange on the side portion stopping at a point inside of the rear end of the 105 protecting cover, the side flange having its front end pivotally connected with the top burner portion whereby that portion of the protecting cover extending in rear of the said flange portion will lie behind said burner portion when the top is raised.

7. A gas range comprising a top burner portion, a swinging cover therefor, said swinging cover having an inwardly extending flange on its forward edge and a flange on its outer side, said cover pivotally connected with the burner portion and located at a point in front of the rear edge of the top burner portion and also of the protecting top, the outer flange adapted to have that portion that extends in rear of the pivotal connection to telescope the adjacent vertical wall of the top burner portion when the protecting 115 cover is elevated and to lie in a horizontal plane above the said burner portion when the cover is lowered to a horizontal position.

8. The combination with a gas range having a top burner portion, of a swinging cover 120

125

for the said burner portion adapted to conceal it when the cover is lowered to a horizontal position, said cover having its outer end and outer side provided with an inwardly projecting flange portion, said flange portion pivotally connected with the burner portion inside of the rear edge of the cover, the rearward portion of the cover located back of the pivotal point adapted to lie in a vertical plane behind the burner portion when it is raised and that portion of the said side flange beyond the pivotal point adapted to lie vertically outside of the adjacent wall of the burner portion when the cover is raised and to lie in a horizontal plane when the cover is lowered, the parts adapted to operate as specified.

9. The combination of a gas range comprising a top burner portion, a swinging protecting cover for the top burner portion and of a dimension to substantially conceal the same when in a horizontal position, said protecting cover having an inwardly extending flange on side portions and one end, said flange on the inner side portion stopping at a point in front of the rear edge of the cover and the opposite side flange extending rearward substantially to the rear edge of the said cover, said side flanges pivotally connected with the top burner portion at points in a horizontal plane with the inner end of the said inner side flange, the parts operating as described.

10. A new range comprising an oven portion, a top burner portion located at one side thereof, the top burner portion having a box-like portion movably connected with the top burner portion whereby the said box-like portion may be moved to horizontal position for concealing the said burner portion and to vertical position with the top of the box-like portion in rear of the burner portion and one side of the box-like portion located at one side of the burner portion.

45 11. A gas range comprising a rectangular shaped burner portion, a swinging cover therefor, said swinging cover pivoted to the top burner portion of the range at a point approximately half way between its front and rear edges said cover operating for the purpose set forth.

12. A range having a top burner portion, a swinging cover pivotally connected with said top burner portion at a point intermediate the front and rear edges of said portion and intermediate the front and rear edges of the cover, a spring positioned beneath said range burner portion and having its lower end connected with the range structure, said swinging cover having an open rear end, a member passing through the top burner portion of the range and the open rear end of the cover and interconnecting the spring and the cover, and the connection of said member with the cover being at a point above the

pivotal connection of the cover with the range top burner portion, the parts arranged for the purpose described.

13. A gas range comprising an oven portion and a top burner portion adjacent thereto, the top of said oven portion being higher than the top burner portion, a hinged enclosing protecting cover for the top burner portion, said cover hinged substantially in the horizontal plane of the upper end of said top burner portion so that its front edge projects above the top burner portion when in a vertical position and when in the horizontal position its said front edge is in substantially the same plane as the top of said top burner portion and concealing the same and the top of the protecting cover is approximately level with the top of the oven portion.

14. A gas range comprising a rectangular shaped top burner portion, an oven projecting above the burner portion and a swinging cover therefor, said swinging cover pivoted to the top burner portion of the range a distance from its rear edge substantially equal to the height of said oven above the top burner portion whereby it operates in its horizontal and vertical positions substantially as described.

In testimony whereof I hereunto affix my signature.

ARTHUR STOCKSTROM.
